UNITED STATES PATENT OFFICE.

CHARLES WALTER WATKINS, OF DORRANCETON, PENNSYLVANIA.

AUTOMATIC STOP FOR MINE-CARS.

1,287,536.

Specification of Letters Patent. Patented Dec. 10, 1918.

Application filed October 2, 1918. Serial No. 256,540.

To all whom it may concern:

Be it known that I, CHARLES W. WATKINS, a citizen of the United States, residing at Dorranceton, in the county of Luzerne and 5 State of Pennsylvania, have invented certain new and useful Improvements in Automatic Stops for Mine-Cars, of which the following is a specification, reference being had to the accompanying drawings.

10 This invention relates to an improved automatic stop for mine cars, and has for its primary object to provide a very simply constructed and durable apparatus for effectively stopping a run-away mine car at 15 the end of a grade to thereby prevent the derailing and possible wreckage of the car.

It is a more particular object of my invention to provide automatic means mounted in the track at the end of the grade which 20 will also prevent the possibility of a rear end collision between a car which has been stopped and a following car.

It is also an important object of the invention to provide means whereby when the 25 device is actuated to release one car, it is automatically reset so as to stop a following car.

The invention further has for one of its detail objects to provide a mechanism automatically actuated by the mine car cage for operating the stop device to release a car 30 held thereby.

My invention further contemplates the provision of improved means for effectively 35 cushioning the shock or jar upon the parts of the stop device and causing a rebound of the car upon the track rails to thereby obviate the possibility of breakage of the car axle or other parts thereof.

40 With the above and other objects in view, the invention consists in the detail construction, combination and relative arrangement of the several parts as will be hereinafter more particularly described, subsequently 45 claimed and illustrated in the accompanying drawings in which similar reference characters designate corresponding parts throughout the several views, and wherein:—

Figure 1 is a side elevation showing one 50 car being released from the stop device and a second car about to strike the stop bars and also illustrating the mechanism actuated by the mine cage for moving the stop bars to released position;

55 Fig. 2 is a longitudinal section through the bar stop;

Fig. 3 is a top plan view; and

Fig. 4 is a section taken on the line 4—4 of Fig. 3.

Referring in detail to the drawings, 5 60 designates a series of supporting ties which are suitably spaced apart, and upon which the track rails, shown at 6, are securely spiked or otherwise fixed. Between the track rails, a series of longitudinally extending metal straps 7 are arranged on the ties 5 and anchor bolts 8 are engaged through the ties and have headed ends disposed in countersunk openings in the metal straps. The straps 7 constitute a base plate. 70

A second series of metal straps 9 extend in parallel relation to the straps 7 and are suitably spaced above the latter straps. The ends of the straps 9 are downwardly inclined, as shown at 10, and secured to the 75 base straps 7 at their extremities. Heavy metal bracing blocks 11 are interposed between the inclined ends 10 of the straps 9 and the straps 7, and suitably secured to the two series of straps. The block 10 at the 80 rear end of the device is formed upon its front end face with a plurality of spaced lugs 12 for a purpose which will presently appear.

A sliding head 13 is engaged between the 85 medial portions of the base straps 7 and the upper series of straps 9 and is longitudinally movable with respect thereto. This head is formed with an opening and bosses 14 on the side faces of said block at the ends of 90 the opening. A shaft or axle 15 is mounted for rocking movement in the opening of the head block and upon the ends of this shaft, which projects beyond the opposite sides of the block 13, the stop bars 16 are secured, 95 each of said bars having a boss or collar 17 formed upon its outer side face and through coinciding openings in said boss and the end of the shaft, a cotter pin or other suitable securing means for the stop bar is engaged. 100 It will, however, be understood that the stop bars may be keyed upon the ends of said shaft and held against rotation relative thereto by any other preferred means. Each of the bars 16 is formed at its forward end 105 with an upwardly projecting toe 18, with which the car wheel axle is adapted to engage when the stop bars are in their normal positions. Each of said bars is likewise provided at its opposite or rear end with an 110 upwardly inclined shoulder or extension 19. To the latter end of each stop bar and to

the lower edge thereof, a guide strap or loop 20 is fixed at its ends.

21 designates a rock shaft mounted upon one of the ties 5 and having spaced cranks 22 formed therein which are respectively engaged in the guide loops 20. To this shaft, at one of its ends, a lever 23 is fixed, while to the other end of the shaft, an arm 24 is secured, said arm projecting from the shaft 10 at right angles to the direction of the lever.

The slide block or head 13 is likewise provided upon its rear end face with a series of spaced lugs 25. Heavy coiled cushioning springs 26 are engaged at one of their ends 15 upon the lugs 25 and have their other ends engaged upon the lugs 12 which project from the end of the rear bracing block 11. These springs normally act to urge the block or head 13 and the strap bars 16 in a forward direction so that the cranks of the shaft 21 will be normally engaged in the rear ends of the guide loops 20. Upon the lever 23, a counterbalancing weight 27 is secured, and this weight, when disposed at 25 one side of the axis of the shaft 21, serves to retain the stop bars 16 in their normal positions, as shown in full lines in Fig. 1.

When the mine car arrives at its point of destination where the stop device is located, 30 the front axle thereof strikes the front upper ends of the stop bars at the toe portions 18 thereof. The force of the impact causes the stop bars to be moved rearwardly, together with the slide block 13 and against the action of the cushioning springs 26. The car immediately rebounds, the springs returning the stop bars 15 to their former positions. Thus, the movement of the car is checked and cushioned and the possibility 40 of the car leaving the rails and resulting in the wreckage thereof is obviated. When the lever 23 is swung to the right from its full line position, the cranks of the shaft 21 are moved upwardly, thereby raising the 45 rear ends of the stop bars 16 and lowering the forward ends of said bars so that the toe portions 18 will be disposed below the car axle. Of course, upon the release of the car, its movement continues and the 50 front axle thereof strikes the upwardly inclined shoulders, the toe portions at the rear ends of the bars 16 forcing the stop bars in a downward direction at their rear ends and thereby moving the lever 24 over to the left hand side of the center of the shaft 21. The weight 27 on said lever then moving by gravity continues the swinging movement of the lever and through the medium of the cranks 22 acting upon the guide loops 20, the downward movement of the rear ends of the stop bars is continued, thus again elevating the forward ends of said bars to their normal positions where they will engage with the axle of the following 65 car.

The mine cars are delivered upon the track rails 6 from the mine cage, and in order to prevent the possibility of collision between two cars traveling on the rails 6, I have provided means actuated by the cage 70 to operate the stop bars 16 and release the car held thereby. This mechanism consists of a bell crank lever 28 pivoted, as at 29, upon a suitable support adjacent the mine cage shaft. One arm of this lever is horizontally disposed and to the same a stop bar 30 is fixed. 31 designates a trip member bifurcated at one end to receive the end of the horizontal lever arm and pivoted upon said arm, as at 32. This trip member 80 is formed with a lug 33 to engage the stop 30 to limit the pivotal movement of the trip in one direction. The trip member 31 at its other or free end projects into the mine shaft and is adapted to be engaged by the cage floor, indicated at F, in the downward movement of the cage to actuate the lever 28. The other or vertical arm of the lever 28 is connected by a rod or other suitable element 34 to one arm of the bell crank lever 35, the other arm of which, indicated at 36, is connected by means of a link 37 to the arm 24 fixed on the end of the rock shaft 21. Assuming that the stop bars 16 are in the full line positions shown in Fig. 95 1, when the mine cage descends with another car to be moved from the cage upon the track rails 6, the cage floor strikes the trip member 31 and as this trip member is held against downward movement relative to the lever arm by the stop 30, said lever will be actuated and through the medium of the bell crank 36, link 37 and arm 25, the shaft 21 is rocked as above explained so that the cranks 22 thereof will operate the 105 stop bars 16, lowering the forward ends of said bars to release the car. The front axle of the car engaging the rear ends of the stop bars as above explained, reverses the movement of the crank shaft and returns 110 the stop bars to their normal positions. The distance between the front and rear axle of the car and the length of the stop bars is such that a second car moving from the cage along the track rails cannot possibly 115 strike the rear end of the car just released from the stop device before the front axle of the second car engages the ends of the bars 16. Thus, all possibility of collision between two cars moving from the mine 120 cage over the rails 6 will be obviated.

It will, of course, be understood that in the return of the stop bars to their normal positions, the bell crank lever 28 is also returned to its normal position so that the trip 125 member 31 will extend horizontally over the edge of the cage floor. In the upward movement of the cage, the floor engages the trip member and lifts the same relative to the arm of the bell crank lever, thus permitting 130

of the movement of the cage without actuating the stop mechanism. This relative movement of the trip member is limited by the stop 30, said trip member returning by gravity to its normal position.

I preferably provide in spaced relation to the rear end of the stop device an additional tie, indicated at 38, to the side of which a metal plate 39 is fixed. This metal plate is adapted to be engaged by the rear ends of the stop bars 16 when said bars are driven with great force in a rearward direction, as when a run-away car on a steep grade strikes the forward ends of the stop bars. Thus, in such cases, the parts of the device will not be injured or broken. No serious injury will occur to the mine car even in such cases, though the axle might be slightly bent. The springs 28 are amply strong enough to sustain all ordinary shocks or jars which might reasonably be expected in the ordinary operation of the car.

Preferably, longitudinally disposed guide cleats 13' are fixed to the upper and lower faces of the head 13, at each side thereof, said cleats effectually preventing the transverse shifting movement of the head relative to the spaced metal straps 7 and 9.

When the stop bars 16 are in their normal positions, as seen in full lines in Fig. 1, they are effectually locked against tilting movement, whereby the car might be released by reason of the angular relation of the cranks 22 with respect to the angle of said stop bars.

From the foregoing description, taken in connection with the accompanying drawings, it is believed that the construction, manner of operation and several advantages of my invention will be clearly and fully understood. The apparatus has been thoroughly tested in practical use and has been found to effectively accomplish the desired purpose. I have herein referred to a plurality of metal straps in the construction of the body of the device, but it is apparent that a single plate may be substituted for such straps if desired. By providing the inclined portions 10 of this body, loose couplings and other parts of the cars may freely drag over the same between the stop bars 16. The mounting and arrangement of the cranked rock shaft and also of the several parts actuated by the mine car cage, are capable of considerable variation, and it is to be understood that I reserve the privilege in practice of resorting to all such legitimate alternative modifications of my invention as herein described, as may be fairly embodied within the spirit and scope of the appended claims.

I claim:—

1. A stop device for cars including vertically tilttable and longitudinally movable stop members mounted between the track rails, means for yieldingly limiting longitudi-

nal movement of said members in one direction, said members when in their normal positions being adapted to engage at one of their ends with the front axle of a car, and means for tilting said members to release the cars, the other ends of said members being engaged by the front axle of the moving car to return said members to their normal positions.

2. A stop device for cars including vertically tilttable and longitudinally movable stop members mounted between the track rails, means for yieldingly limiting longitudinal movement of said members in one direction, said members when in their normal positions being adapted to engage at one of their ends with the front axle of a car, and counterweighted means for tilting said members and retaining the same in their operative or inoperative positions, the front axle of the car when released engaging the other ends of said members to return said members to their effective positions.

3. A stop device for cars including a sliding head mounted between the track rails, means for yieldingly cushioning the movement of said head in one direction, vertically tilttable stop bars mounted upon said head and movable therewith, and means operatively connected to said bars at one of their ends to retain the same in position for engagement at their other ends with the front axle of a car and to tilt said members to release the car; the axle of the moving car being adapted to engage the first named ends of said members and return the same to their normal effective positions.

4. A stop device for cars including guide means arranged between the track rails and a horizontally movable head mounted in the guide means, means for yieldingly cushioning the movement of said head, tilttable stop bars mounted on the head and movable therewith, a rock shaft, spaced cranks in the rock shaft respectively connected to said bars at one of their ends, a counterweighted lever connected to the rock shaft and operable to hold said bars against casual, tilting movement and retain the same in their effective or ineffective positions, said bars being adapted for engagement at one of their ends with the front axle of a car and being movable under impact with relation to the rock shaft.

5. A stop device for cars including guide means arranged between the track rails, a head slidably mounted in said guide means, vertically tilttable bars carried by the head and movable therewith, a rock shaft having spaced cranks therein, said bars being operatively connected at one of their ends to the respective cranks and movable relative thereto, means for cushioning the sliding movement of said head, said bars in one position of the rock shaft being adapted for en-

gagement at one of their ends with the front axle of a car, and automatically actuated means connected to said shaft to rock the same and tilt said stop members, whereby the car is released for movement upon the track, the car axle coacting with said members to return the same to their normal effective positions.

6. A stop device for cars including guide means arranged between the track rails, a head slidably mounted in said guide means, vertically tiltable bars carried by the head and movable therewith, a rock shaft having spaced cranks therein, said bars being operatively connected at one of their ends to the respective cranks and movable relative thereto, means for cushioning the sliding

movement of said head, said bars in one position of the rock shaft being adapted for engagement at one of their ends with the front axle of a car, a trip member adapted to be engaged and actuated by the mine cage in its movement in one direction, and means operatively connecting the trip member to said rock shaft to actuate the latter and tilt said members to release the car, the car axle coacting with said members to return the same to their normal effective positions.

In testimony whereof I hereunto affix my signature in the presence of two witnesses.

CHARLES WALTER WATKINS.
